[57] CLAIM

The ornamental design for a personal computer, as shown and described.

DESCRIPTION

FIG. 1 is a front view of a personal computer showing our new design;

FIG. 2 is a right side view thereof;

FIG. 3 is a back view thereof;

FIG. 4 is a left side view thereof;

FIG. 5 is a top plan view thereof;

FIG. 6 is a bottom plan view thereof; and,

FIG. 7 is a perspective view thereof.

FIGS. 1-4 are drawn on an enlarged scale and the key is shown in broken lines in the figures for illustrative purposes only and forms no part of the claimed design.
